UNITED STATES PATENT OFFICE

115,213

DESIGN FOR A TELEPHONE LAMP OR SIMILAR ARTICLE

Arthur T. McShane and Harry E. Tyler,
Columbus, Ohio

Application February 7, 1938, Serial No. 74,922

Term of patent 3½ years

To all whom it may concern:

Be it known that we, Arthur T. McShane and Harry E. Tyler, citizens of the United States, residing at Columbus, Franklin County, Ohio, respectively, have invented a new, original, and ornamental Design for a Telephone Lamp or Similar Article, of which the following is a specification, reference being had to the accompanying drawing, forming a part thereof.

Fig. 1 is a perspective view of the telephone lamp or similar article showing our new design;

Fig. 2 is a top plan view thereof.

We claim:

The ornamental design for a telephone lamp or similar article, as shown.

ARTHUR T. MCSHANE.
HARRY E. TYLER.
